UNITED STATES PATENT OFFICE.

LOUIS J. JOHNSON, OF MISHAWAKA, AND HARRY L. JOHNSON, OF INDIANAPOLIS,
INDIANA, ASSIGNEES TO JOHNSON BROS. ENGINEERING CORPORATION, OF SOUTH
BEND, INDIANA.

OUTBOARD MOTOR.

Application filed June 16, 1924. Serial No. 720,318.

To all whom it may concern:

Be it known that we, LOUIS J. JOHNSON, a citizen of the United States, residing at Mishawaka, in the county of St. Joseph and 5 State of Indiana, and HARRY L. JOHNSON, a citizen of the United States, residing at Indianapolis, in the county of Marion and State of Indiana, have invented certain new and useful Improvements in Outboard 10 Motors, of which the following is a specification.

The invention relates to outboard motors particularly of the type used in connection with small craft wherein the motor is pivotally mounted and movable, and has for 15 its object to provide in connection with a motor of this character, means whereby when the motor comes into engagement with an obstruction, for instance a log, rock or sand bar, the initial shock of the impact 20 will be yieldably taken up and absorbed, thereby reducing the strain on the motor.

A further object is to provide a pivoted outboard motor with a pivoted obstruction 25 engaging arm extending downwardly forwardly of the free end of the casing and having its end yieldably connected to the casing and forming means for taking up the initial shock when coming into engagement 30 with an obstruction, and relieving the strain on the motor, incident to the starting of the tilting operation thereof. The device is particularly adapted for use in connection with motors of the type set forth in our application for patent filed the 16th day of 35 June, 1924, Serial No. 720,317.

A further object is to provide means whereby the pivoted arm will form a yieldable stop when the motor moves from a 40 tilted to a vertical operative position, thereby reducing the strain on the motor incident to shock of a sudden stopping thereof in its pivotal movement.

With the above and other objects in view 45 the invention resides in the combination and arrangement of parts as hereinafter set forth, shown in the drawing, described and claimed, it being understood that changes in the precise embodiment of the invention may 50 be made within the scope of what is claimed without departing from the spirit of the invention.

In the drawings:—

Figure 1 is a vertical longitudinal sectional view through the stern of a boat, 55 showing the motor carried thereby and in operative position.

Figure 2 is a view similar to Figure 1, showing the lower end of the pivoted motor as it approaches the operative position and 60 the pivoted shock absorbing arm starting its shock absorbing operation.

Figure 3 is a detail perspective view of the lower portion of a recess in the stern of the boat, showing slotted members carried 65 thereby for the reception of the shock absorbing arm.

Figure 4 is an enlarged detail sectional view through the lower end of the propeller drive shaft casing, showing the yieldable 70 spring means.

Referring to the drawing, the numeral 1 designates the hull of a boat and 2 a recess in the stern thereof. Pivotedly mounted at 3 within the upper end of the recess 2 is a motor 4 of a general outboard type, as set forth in the application above referred to, and wherein the muffler 5, and the transverse plate 6 forms a closure for the rear end of the recess 2, and a horizontal disposed bifurcated plate 7, in combination with a yieldable member 8 carried by the muffler at opposite sides of the drive shaft casing 9 forms a bottom closure for the recess. It has been found in outboard motors, and particularly motors of the character set forth, 80 when the lower end of the motor engages a log or obstruction in the water, the initial shock and jar on the motor, incident to the impact, damages the motor and strains various parts thereof. To obviate this difficulty a yieldable guard arm 10 is provided, which arm is pivotally connected at 11 to the pivotally mounted motor and extends downwardly forwardly of the motor casing 9. The guard arm 10 extends through the slot 7a in the bifurcated plate 7, and the slot 12 in the lower flange 13 of the channeled member 14, and also through a slot 15 in the closure plate 16 carried by the casing 9, 85 and which closure plate, when the motor is in operative position as shown in Figure 1 is in substantially the same plane as the bottom 17 of the boat. Arm 10 extends

95

downwardly and forwardly, and thence downwardly and rearwardly to the forward side of the lower end 18 of the drive shaft casing, therefore it will be seen that 5 when the boat runs into shoal water, for instance over a sand bar or hits a log or rock, the arm 10 will be forced rearwardly, at which time the piston rod 19, which has a link connection 20 with the arm 10, will be 10 forced rearwardly, thereby compressing the coiled spring 21, surrounding the reduced guide portion 22 of the piston rod, consequently the initial shock of the impact is taken up and absorbed, at the starting of the 15 tilting operation to the dotted line position shown in Figure 1, consequently the propeller 23 will not come into contact with the obstructions. The reduced portion 22 of the piston rod is connected to the piston 24 which engages one end of the coiled spring 21 and it is slidably mounted in a movable plug 25, therefore it will be positively guided in its axial movement and will not bind. The link connection 20 allows freedom of 20 movement during the shock absorbing operations.

After a tilting operation of the motor by engagement of the arm 10 with an obstruction, the motor will automatically move to vertical operative position after 30 passing the obstruction, and which movement is a relatively quick one under the influence of the propeller 23, which rotates at all times, therefore it will be seen that 35 considerable shock would take place on the motor if means were not provided for taking up the shock. Under the above conditions the arm 10, as the lower end of the motor approaches operative position passes 40 into the slot 12 of the flange 13 as clearly shown in Figures 2 and 3 and the arm is stopped by engagement with the inner end of the slot 12, therefore the continued forward movement of the free end of the motor 45 will compress the spring 21, thereby taking up the shock, and obviating sudden stopping of the free end of the motor. As the free end of the motor continues in its movement to operative position, the forward end 50 of the plate 16 comes into engagement with a strip of yieldable material, for instance rubber, disposed in the channel 14, said yieldable material being designated by the numeral 26, consequently the shock of stopping 55 is additionally checked and at the same time a relatively tight joint is provided when the plate 16 forms a relatively tight closure for the lower end of the reduced portion 2^a of the recess 2 in the stern of the boat.

From the above it will be seen that a yieldable obstruction engaging device is 60 provided for outboard motors of the pivotally mounted type, and which obstruction 65 engine device will absorb the shock incident

to the motor coming in contact with obstructions and will also absorb the shock incident to the motor returning to normal operative position, and one which is particularly adapted for use in connection with a 70 pivoted motor mounted in a recess in the stern of a boat and extending through and carrying closure plates for the recess.

The invention having been set forth what is claimed as new and useful is:—

1. The combination with a pivotally mounted motor, said motor being carried by a boat, of a guard for the free end of said motor, said guard being yieldably mounted on the motor and yieldable in relation thereto and forming means whereby initial shocks will be taken up.

2. The combination with a pivotally mounted outboard motor, a propeller carried by the free end of said motor, said motor being pivotally connected to a boat, of a yieldable shock absorbing obstacle engaging member carried by the free end of the motor and yieldable in relation to the motor.

3. The combination with a pivotally mounted outboard motor, a propeller carried by the free end of said motor, of a yieldable shock absorbing obstacle engaging member carried by the free end of the motor forwardly of the propeller and yieldable in relation to the motor.

4. The combination with a pivotally mounted outboard motor, a propeller carried by the free end of said motor, an arm pivotally connected to the motor and extending towards its free end forwardly of the propeller, and a yieldable connection between the arm and the free end of the motor.

5. The combination with a pivotally mounted outboard motor, a propeller carried by the free end of said motor, an arm pivotally connected to the motor at its forward side and terminating forwardly of the free end of the motor and forwardly of the propeller, and a yieldable connection between the arm and the motor.

6. The combination with the free end of a pivotally mounted outboard motor, a propeller carried by said free end, of an obstacle engaging and shock absorbing member carried by said free end of the propeller, said member comprising an arm pivoted to the motor, said arm extending downwardly forwardly of the propeller, a coiled spring disposed in a chamber of the free end of the motor, and means carried by said arm and cooperating with the spring whereby initial shocks of impacts will be taken up by the spring and relieved from the motor.

7. The combination with a pivotally mounted outboard motor carried by a boat, of a yieldably mounted propeller guard,

said guard forming means whereby shocks of impacts will be taken up as the motor is moved from operative to inoperative position, and from inoperative to operative position.

8. The combination with a pivotally mounted motor, said motor being pivotally connected to a boat, of a shock absorbing arm pivoted to the motor and disposed between the motor and the boat, said shock absorbing arm forming a guard for the free end of the motor, and a yieldable buffer between the motor and the boat.

9. The combination with a pivotally mounted motor, said motor being pivotally mounted in a recess in a boat, plates disposed within the recess and carried by the motor and forming closures for said recess, of a pivoted guard arm carried by the motor

and extending downwardly through slots in the plates to a position adjacent the free end of the motor, yieldable connections between the arm and the motor, said arm forming a shock absorber upon initial upward movement of the motor and upon final downward movement of the motor.

10. The combination with a pivotally mounted motor, said motor being pivotally mounted on a boat, of a pivoted yieldably connected guard arm interposed between the motor and the boat and forming shock absorbing means upon initial upward movement of the motor and upon final downward movement of the motor.

In testimony whereof we affix our signatures.

LOUIS J. JOHNSON.

HARRY L. JOHNSON.
